T. E. FRYE

By Watson E. Coleman

Attorney.

UNITED STATES PATENT OFFICE.

THOMAS E. FRYE, OF TERRE HAUTE, INDIANA, ASSIGNOR TO JOSEPH H. HAUCK, OF TERRE HAUTE, INDIANA.

CONDIMENT-HOLDER.

1,217,295.

Specification of Letters Patent. Patented Feb. 27, 1917.

Application filed April 19, 1916. Serial No. 92,251.

To all whom it may concern:

Be it known that I, THOMAS E. FRYE, a citizen of the United States, residing at Terre Haute, in the county of Vigo and State 5 of Indiana, have invented certain new and useful Improvements in Condiment-Holders, of which the following is a specification, reference being had to the accompanying drawings.

10 This invention relates to condiment holders and more particularly for holders for pepper or salt or like condiments.

The general object of this invention is the provision of a very simple holder or shaker 15 so constructed that it may contain two different condiments either of which may be discharged from the shaker by rotating the cap of the shaker a predetermined distance so as to bring one set of holes in the cap in 20 an operative position and the other set of holes out of an operative position.

A further object of the invention is the provision of means whereby the cap may be normally retained upon the top of the shaker 25 but may be readily disengaged therefrom in order that the cap may be cleaned.

Still another object is the provision of a 30 very simple means for retaining the cap in its operative position and detachably holding the cap so that one or the other of the sets of holes may be in operative position.

Other objects will appear in the course of the following description.

The invention is illustrated in the accompanying drawings wherein,

Figure 1 is a vertical diametrical section through my improved shaker, in a plane at right angles to the plane of the partition 5;

Fig. 2 is a vertical diametrical section 40 taken on a plane at right angles to the plane of Fig. 1, the partition 5 being shown in elevation;

Fig. 3 is an elevation of the shaker;

Fig. 4 is a section on the line 4-4 of 45 Fig. 1;

Figs. 5 and 6 are top views of the cap showing it in different adjusted positions;

Fig. 7 is a cross sectional view on the same 50 lines as Fig. 4, but showing a modified way of limiting the rotation of the cap;

Fig. 8 is a fragmentary section on the line 8-8 of Fig. 7; and

Fig. 9 is a fragmentary sectional view on the line 9-9 of Fig. 1 looking upward to

show the conformation of the walls of the 55 slot 11.

Referring to these drawings, 2 designates the body of the receptacle or shaker which is approximately cylindrical in form but may have any desired ornamental configuration. 60 The bottom wall 3 of the shaker is above the lower edge of the side wall and is formed with two openings normally closed by plugs 4. Extending downward through the body 2 is a partition 5 which divides the interior 65 of the shaker into two chambers 6 and 7, one of the chambers being designed for salt and the other for pepper.

The body 2 is closed at its upper end by a transversely extending wall 8, one half of 70 which is perforated with relatively small openings 9 and the other half of which is perforated with relatively large openings 10. The large perforations are of course, disposed over the salt compartment 6, while the 75 small perforations are disposed over the pepper compartment. At its center the top wall 8 is formed with a vertically extending T- slot 11. On the side wall of the body 2 adjacent the upper end there is a lug 12, which 80 lug is cut away upon its outer face at its middle for a predetermined distance as at 13, the ends of this cut away portion terminating in inwardly extending recesses 14. This leaves at the ends of the lug the stops 85 15. The upper wall of the T-shaped slot 11, as illustrated in Fig. 9, is transversely recessed or countersunk as at 11a.

The cap 16 as illustrated in Fig. 1, has a downwardly extending flange and at its 90 middle the cap is provided with a depending pin 17, the lower end of which is T-shaped as at 18. This T-shaped pin may be inserted through the slot 11 and then when the cap is turned the arms of the T-shaped 95 pin will engage beneath the top 8 and in said recesses 11a and lock the cap in place, but permit its rotation. Extending downward from the flange of the cap is a finger 19 which is preferably of resilient material 100 and this finger normally engages against the face of the lug 12 and is disposed, of course, between the stops 13. The finger is resiliently urged inward and thus travels between the stops and engages in the notches 14. 105 The cap 16 is perforated with two sets of perforations, one set being relatively small and the other relatively large. The perfora-

tions 9 and 10 and the perforations in the cap are so arranged that when the cap is turned in one direction to carry the finger 19 into one of the notches, the small perforations in the cap will register with the small perforations 10 in the upper end of the body 2 but the perforations 9 will be closed and vice versa, when the cap is turned in the other direction, the perforations 9 will 10 be in registration with the perforations in the cap while the perforations 10 will be closed. Under this circumstance it will be obvious that the rotation of the cap in one direction will permit the discharge of pepper 15 from the shaker while the rotation in the other direction will permit the discharge of salt from the shaker and it will be plain that if it is desired to remove the cap entirely, it is only necessary to spring out 20 the finger 19 from its engagement with the face of the lug 12 whereupon the cap may be rotated to a position which will bring the arms of the T-shaped pin into alignment with the slot 11 and that then the cap may 25 be withdrawn. It is preferable that the cap shall be made detachable but I do not wish to be limited to this. While the pin 17 might be made in one piece with the cap 16, I preferably have it pass loosely through 30 the cap and formed at its outer end with a head and disposed within the head and the cap a coil spring 20 which bears down upon the cap and forces upward on the pin so as to hold the cap firmly engaged with the top 35 of the body 2.

In Figs. 7 and 8 I show a modification of the construction illustrated in Figs. 1 to 6 wherein, in place of the finger 19, I provide a stud 19^a which is formed integral with the 40 body 2^a, this stud extending into a recess 21 formed in the wall of the cap on the inside face thereof, the ends of this recess forming stops for limiting the amount of rotation of the cap. In Figs. 7 and 8, 2^a designates the 45 body, 4^a the plugs, 5^a the middle partition, 6^a and 7^a the compartments for condiments, 8^a the top wall, 9^a the perforations in the top wall and 16^a the cap.

The manner in which the device is to be 50 used is evident from what has gone before. The advantages of the device reside in the fact that both pepper and salt or any other two condiments of like character may be contained in one shaker or receptacle and either one discharged as may be desired. Furthermore it will be seen that the device 55 is very simple, may be cheaply made and may have any desired ornamental character and is extremely convenient for the purpose designed. Furthermore, it is obvious

that the device may be readily kept clean which it is difficult to do with shakers that are ordinarily constructed.

Having described my invention, what I claim is:

1. In a condiment holder of the character described, a body having a longitudinally extending partition wall dividing it into chambers, and the body having a lug formed on the outer face having notches, a cap rotatably mounted upon the upper end of the body and a resilient finger mounted on the cap and extending over and bearing against the face of the lug, the upper end of the body being formed with a plurality of sets of perforations one for each condiment, and the cap being also formed with a plurality of sets of perforations. 70

2. In a condiment holder of the character described, a body having its upper end formed with perforations and with a central slot, a perforated cap disposed over the upper end of the body, a depending T-shaped stud engaged with the cap and engaged in said slot whereby to support the cap for rotation upon the body, and means for detachably holding the stud with its arms approximately at right angles to the length of the slot. 80

3. In a condiment holder of the character described, a body having its upper end formed with perforations and with a central slot, a perforated cap, a T-shaped pin passing through the cap and having its T-shaped head engaging in said slot and normally disposed at right angles thereto, a head on the pin, and a coil spring disposed between the head and the cap and bearing against the latter. 95

4. In a condiment holder of the character described, a body having its upper end formed with perforations and with a central slot, a perforated cap, an inverted T-shaped pin passing through the cap and having its T-shaped head engaging in said slot and normally disposed at right angles thereto, the under face of the upper end of the body on each side of the slot being formed with a countersink in which said T-shaped head is adapted to engage, a head on the pin, and a coiled spring disposed between the head and the cap and yieldably urging upward on the pin. 100

In testimony whereof I hereunto affix my signature in the presence of two witnesses. 110
